Clifford E. Denney

UNITED STATES PATENT OFFICE.

MILLER REESE HUTCHISON, OF WEST ORANGE, NEW JERSEY.

DESIGN FOR A CASING FOR STAPLING AND FASTENING MACHINES.

53,072.

Specification for Design.

Patented Mar. 11, 1919.

Application filed February 2, 1917. Serial No. 146,292. Term of patent 7 years.

To all whom it may concern:

Be it known that I, MILLER REESE HUTCHISON, a citizen of the United States, residing at West Orange, in the county of Essex and State of New Jersey, have invented a new, original, and ornamental Design for Casings for Stapling and Fastening Machines, of which the following is a specification, ref-

erence being had to the accompanying drawing, forming a part thereof, which shows the casing in perspective.

I claim:

The ornamental design for a casing for stapling and fastening machines, as shown.

MILLER REESE HUTCHISON.
